[57] CLAIM

The ornamental design for a probe for measuring an electric conductivity, as shown and described.

DESCRIPTION

FIG. 1 is a front, top and right side perspective view of a probe for measuring an electric conductivity, showing our new design;

FIG. 2 is a front elevational view thereof, the opposite side being a mirror image thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a reference view showing the state of the probe drawn by a cable in the water of the sea in a suspended state; and the broken lines depicting environmental circumstances of the present article form no part of the claimed design.
